UNITED STATES PATENT OFFICE.

WALTER D. BUTZ, OF NORRISTOWN, PENNSYLVANIA, ASSIGNOR TO PARAMOUNT KNITTING COMPANY, OF CHICAGO, ILLINOIS, A CORPORATION OF ILLINOIS.

RIB-KNITTING MACHINE.

1,120,444.

Specification of Letters Patent.

Patented Dec. 8, 1914.

Application filed May 8, 1914. Serial No. 837,160.

To all whom it may concern:

Be it known that I, WALTER D. BUTZ, a citizen of the United States, residing in Norristown, Pennsylvania, have invented 5 certain Improvements in Rib-Knitting Machines, of which the following is a specification.

The object of my invention is to provide means for locking together the needle cylinder and needle dial of a rib knitting machine without the employment of the usual 10 engaging dogs on the inner side of the cylinder and under side of the dial. This object I attain in the manner hereinafter set forth, reference being had to the accompanying drawings, in which—

Figure 1 is a view, partly in elevation and partly in vertical transverse section of sufficient of a rib knitting machine to illustrate 20 my invention; Fig. 2 is a plan or top view of the same; Fig. 3 is a horizontal section on the line *b*—*b*, Fig. 1; Fig. 4 is a horizontal section on the line *c*—*c*, Fig. 1, and Fig. 5 is a horizontal section on the line 25 *d*—*d*, Fig. 1.

In the drawings, 1 represents part of the fixed base or bed of the machine, 2 a non-rotating needle cylinder secured thereto and 3 a non-rotating needle dial which is mounted upon a spindle 4 depending from an arch 5, the latter being mounted upon studs 6 projecting upwardly from a ring 7 to which rotating movement can be imparted by mechanism common in this class of machines, said ring also carrying a cylinder 8 provided with cams for imparting reciprocating motion to the needles of the needle cylinder. A disk 9 which carries the cams for imparting reciprocating movement to the 30 dial needles is mounted so as to be free to rotate on the spindle 4 and is caused to rotate in unison with the cam cylinder 8 by suitable connection between said disk and one of the posts 6, this connection, in the 35 present instance, consisting of a link 10 pivotally connected to the disk 9, as shown in Fig. 3, and having in it an elongated slot 11 through which the post 6 passes, the opposite ends of this slotted portion of the link carrying set screws 12 bearing on opposite sides of the post 6 so that by proper 40 adjustment of these set screws the disk 9 can be moved in one direction or the other so as to cause the cams thereof to reciprocate the dial needles in proper coördination with 55 the reciprocating cylinder needles.

In order to lock the dial 3 and its spindle 4 to the cylinder 2 without the use of the usual interlocking dogs thereon I mount upon the rotating arch 5 of the machine a 60 ring 13 which is prevented from rotating with said arch by means of an arm 14 projecting from said ring and having a rounded and slotted head 15 which fits between flanges 16 on an adjusting screw 17, the latter being adapted to a threaded opening in a fixed post 18 at one side of the machine and being provided with a suitable locking nut 19, as shown in Fig. 2. In order to lock the spindle 4 to this fixed ring 13 I 70 provide a locking bolt 20 which can pass freely through a slot in the spindle, as shown in Figs. 1, 2 and 3, one or other or both ends of this locking bolt engaging slots 21 in a ring 22 (Figs. 1, 4 and 5) which ring 75 is locked to the fixed ring 13, so as to permit of slight circumferential adjustment in respect thereto, by means of a pair of adjusting screws 23 adapted to threaded openings in the ring 13 and engaging with the bases 80 of recesses 24 formed in the ring 22, as shown in Fig. 4, projecting movement of one of these adjusting screws 23 accompanied by corresponding retracting movement of the other of said screws 23 causing such circumferential movement of the ring 22, spindle 4, and dial 3 in respect to the fixed ring 13 as may be necessary to bring the needles of the dial in proper alternating relation to the needles of the cylinder. Independent rings 85 13 and 22 are not absolutely necessary for this purpose, as but a single ring 13 slotted for the reception of the bolt 20 and adjustable by the screw 17 might be used for this purpose, the use of the two rings, however, 90 providing for a double adjustment.

In order to provide a more extended bearing for the locking bolt 20 than that afforded by the spindle 4 alone, I surround said spindle with a hub 25 slotted for the 100 reception and guidance of the bolt, as shown in Fig. 4, and prevented from rotating on the spindle 4 by means of a spline 26 which is fitted to oppositely located grooves in the spindle and hub, as shown in Fig. 4.

Secured to the rotating arch 5 by means 105 of a set screw 27 is an arm 28 which projects from a yarn guide 29, the latter hav-

ing an opening registering with an opening 29^a in the arch 5. The yarn guide 29 is free to rotate in the space between the ring 22 and hub 25, as shown in Fig. 4, and serves 5 to direct the yarn from a fixed guide above the machine to the yarn guide 35 on the rotating dial cam plate 9. A cap plate 30 is mounted so as to be free to rotate upon the ring 22 and a shouldered portion of the hub 25, as shown in Fig. 1, and serves to prevent 10 access of dust, lint, or other foreign matter to the parts below the same. Also secured to the rotating arch 5 by means of screws 31 to the rotating arch 5 by means of screws 31 15 is a cam 32 best shown in Fig. 5, this cam is a cam 32 best shown in Fig. 5, this cam 20 acting first upon one end and then upon the opposite end of the locking bolt and serving to move the same first in one direction and then in the other, so as to carry said ends alternately into and out of the slots formed 25 in the ring 22 for their reception. As shown in Figs. 4 and 5, the high portion of the cam has acted upon the right hand end of the bolt 20 to remove the same from the right hand slot 21 in the ring 22 and out of the 30 path of the rotating yarn guide 29, the opposite or left hand end of the bolt being then in full engagement with the left hand slot 21 in said ring 22, and as the cam and yarn 35 guide rotate said cam will in turn act upon the left hand end of the bolt 20 so as to free the same from the left hand slot 21 and from the path of the yarn guide 29 and at the same time project its right hand end into the right hand slot 21, the length of the bolt 40 20, the extent of its reciprocating movement, and the formation of the cam 32 being such that before one end of the bolt is freed from the slot 21 with which it was in engagement the opposite end of the bolt will have engaged the opposite slot 21, so that at no time will the bolt 20 be entirely free from the ring 22, the result being that the spindle 4 and dial 3 are at all times retained in fixed 45 position.

45 In order to effect vertical adjustment of the needle dial in respect to the needle cylinder the upper end of the spindle 4 is threaded for the reception of a nut 33 by adjustment of which the spindle can be raised or 50 lowered to the desired extent, the spline 26 permitting such raising or lowering movement without corresponding rise or fall of the arch 5 or of the locking mechanism above the same.

55 Although I have illustrated my invention as applied to that type of rib knitting machines in which the cylinder and dial are stationary and the cylinder cam ring and dial cam cap rotate, and although it has 55 been designed especially for use in a machine of this type, it can be used in connection with a machine of the reverse type, that is to say, one in which the needle cylinder and dial rotate and the cam cylinder and dial cam cap are non-rotative, the only

change necessary to be effected in this case being the removal of the yarn guide 29 from the arch 5, the securing of the ring 13 to said arch, and the securing of the dial cam cap 9 to the stationary post 18 instead of 70 to the post 6 of the rotating drive ring 7.

Although in my specification and claims I have alluded to the members 13 and 22 as "rings" it will be evident that ring segments can be substituted therefor, if desired, without affecting the operation of the device, hence the term "rings" is to be construed broadly enough to cover the use of such segments if the same are employed. 75

I claim:—

1. The combination of the needle cylinder and dial of a rib knitting machine, a transversely slotted dial spindle, a ring surrounding the same and having oppositely disposed slots therein, a bolt reciprocating 85 through the slot in the spindle and adapted to engage alternately with the slots in said ring to lock the dial spindle against rotary movement in either direction, and a cam for causing such lateral reciprocation of the bolt, said parts being so disposed that one end of the bolt will always be engaged with one of the ring slots before its opposite end is disengaged from the opposite slot. 95

2. The combination of the needle cylinder and dial of a rib knitting machine, a transversely slotted dial spindle, a ring surrounding the same and having oppositely disposed slots therein, a bolt reciprocating 100 through the slot in the spindle and adapted to engage alternately with the slots in said ring to lock the dial spindle against rotary movement in either direction, a cam for causing such lateral reciprocation of the 105 bolt, said parts being so disposed that one end of the bolt will always be engaged with one of the ring slots before its opposite end is disengaged from the opposite slot, and a hub surrounding the spindle and secured 110 thereto, said hub having therein bolt guiding slots registering with the slot in the spindle.

3. The combination of the needle cylinder and dial of a rib knitting machine, a transversely slotted dial spindle, a ring surrounding the same and having oppositely disposed slots therein, a bolt reciprocating 115 through the slot in the spindle and adapted to engage alternately with the slots in said ring, a cam for causing such lateral reciprocation of the bolt, a ring surrounding said slotted locking ring, and means for effecting circumferential adjustment of one of said rings in respect to the other. 120

4. The combination of the needle cylinder and dial of a rib knitting machine, a transversely slotted dial spindle, a ring surrounding the same and having oppositely disposed slots therein, a bolt reciprocating 130

through the slot in the spindle and adapted to engage alternately with the slots in said ring to lock the dial spindle against rotary movement in either direction, a cam for causing such lateral reciprocation of the bolt, said parts being so disposed that one end of the bolt will always be engaged with one of the ring slots before its opposite end is disengaged from the opposite slot, a ring surrounding said slotted locking ring, and

means for effecting circumferential adjustment of both of said rings.

In testimony whereof, I have signed my name to this specification, in the presence of two subscribing witnesses.
